United States Patent Office

Des. 186,834
Patented Dec. 8, 1959

186,834

FOLDABLE COOKING UNIT

Charles T. Waltman, Chicago, Ill., assignor to Dixie Products, Inc., Cleveland, Tenn.

Application June 18, 1958, Serial No. 51,414

Term of patent 14 years

(Cl. D81—4)

Fig. 1 is a perspective view of a foldable cooking unit showing my new design;

Fig. 2 is a top plan view thereof;

Fig. 3 is a front elevational view thereof; and

Fig. 4 is a side elevational view of the same.

The rear of the article is substantially plain.

I claim:

The ornamental design for a foldable cooking unit, as shown and described.
